(57) **CLAIM**

I claim the ornamental design for cord and strap combination shoe closure, as shown and described in the drawings.

DESCRIPTION

FIG. 1 is a front perspective view of a cord and strap combination shoe closure in accordance with the new design;

FIG. 2 is a front perspective view thereof showing the strap in the removed position;

FIG. 3 is a front perspective view thereof showing the strap in the closed position;

FIG. 4 is a plan view thereof;

FIG. 5 is a side elevational view thereof;

FIG. 6 is a side elevational view thereof;

FIG. 7 is a front elevational view thereof; and,

FIG. 8 is a back elevational view thereof.
